UNITED STATES PATENT OFFICE

113,929

DESIGN FOR A MIRROR LAMP OR SIMILAR ARTICLE

Maurice Langbaum, Brooklyn, N. Y.

Application January 3, 1939, Serial No. 82,113

Term of patent 3½ years

To all whom it may concern:

Be it known that I, Maurice Langbaum, a citizen of the United States of America, residing in New York city, in the Borough of Brooklyn, county of Kings, and State of New York, have invented a new, original, and ornamental Design for a Mirror Lamp or Similar Article, of which the following is a specification, reference being had to the accompanying drawing, forming part thereof, wherein,

The upper end of the mirror lamp support has substantially the same appearance as the lower end shown in Figure 1.

I claim:

The ornamental design for a mirror lamp or similar article, substantially as shown and described.

MAURICE LANGBAUM.
